RECORD CABINET

Patentee, New Orleans, La.

Application March 22, 1952, Serial No. 19,007

Term of patent 7 years

(Cl. D33—19)

To all whom it may concern:

Be it known that I, Mel Offner, a citizen of the United States and a resident of the city of New Orleans, Parish of Orleans, and State of Louisiana, have invented a new, original, and ornamental Design for a Record Cabinet, of which the following is a specification, reference being had to the accompanying drawings, forming part thereof.

Fig. 1 is a perspective view of a record cabinet showing my new design, in which the undisclosed sides are identical to the two adjacent sides shown.

Fig. 2 is a top plan view thereof.

I claim:

The ornamental design for a record cabinet, as shown and described.

MEL OFFNER.
